[57] CLAIM

The ornamental design for a chair actuator, as shown and described.

DESCRIPTION

FIG. 1 is a top view of a chair actuator showing our new design;

FIG. 2 is a front, elevational view thereof;

FIG. 3 is a right, side, elevational view thereof;

FIG. 4 is a left, side, elevational view thereof;

FIG. 5 is a bottom, elevational view thereof; and,

FIG. 6 is a fragmentary, right, side, perspective view thereof; and,

FIG. 7 is a front perspective view thereof.

The chair shown in broken lines in FIG. 7 forms no part of the ornamental design for a chair actuator of this application.
